CONTAINER

Leo Esterow and Abraham Klein, New York, N. Y.

Application September 17, 1942, Serial No. 458,632

4 Claims. (Cl. 220—55)

This invention relates to receptacles or containers, and particularly to small receptacles such as vanity cases, compacts, cigarette cases, and other small and compact containers capable of use for various purposes. Up to the present time, most of these containers have been stamped from sheet metal or similar material and it is the primary object of the present invention to provide a container which can be satisfactorily made from either metal or other materials, such as wood, plastic composition, or the like, including not only the body of the container, but its operating parts as well, such as the hinge elements and locking means.

Another object of the invention is to provide, in a container or receptacle of this character, a strong and sturdy construction, with parts arranged to permit simplified assembly and resulting in a container of attractive appearance.

Another object of the invention is to provide in a container of the character described, an improved locking means for holding the container closed, the parts of the locking means being of such design and construction that the same may be made of wood or other material.

These and other objects are accomplished by the invention, a more particular description of which will hereinafter appear and be set forth in the claims appended hereto.

Reference is to be had to the accompanying drawing, forming a part hereof in which Fig. 1 is a plan view of a container constructed in accordance with the invention, the locking means being shown in open position; Fig. 2 is a front elevation of the container, the locking means being shown in closed position; Fig. 3 is an edge view of the container; Fig. 4 is a sectional view on the line 4—4 of Fig. 1, looking in the direction of the arrows; Fig. 5 shows the locking member or hasp; Fig. 6 is a plan view of a portion of a container, showing a modified form of lock; Fig. 7 shows a sliding bolt for the lock of the structure shown in Fig. 6; Fig. 8 is a plan view of a portion of a container, showing another modified form of lock; and Fig. 9 is a front elevation of the structure shown in Fig. 8, the cover being raised.

In the structure shown in Figs. 1 to 6, the top or upper section of the container is shown at 1, the bottom or lower section being indicated at 2. These two sections may be of any suitable shape and size and may be made of wood, plastic or of any other suitable material. The rear ends of the sections 1 and 2 are longitudinally grooved as indicated at 3, and in the groove of one of the sections is secured, adhesively or

by any other fastening means, a tubular element 5, disposed in axial alignment with two similar tubular elements 4 similarly secured on the other section of the container. A pintle 11 extends through the three aligned tubular elements 4 and 5 and co-operates therewith in forming the hinge for the two container sections.

The opposite ends of the two container sections are grooved as indicated at 6, the groove in the top or upper container section 1 receiving two spaced cylindrical elements or beads 8 in which are pivotally mounted the pintle portions 10 of a locking loop or hasp 9, shown in detail in Fig. 5.

Secured in the groove 6 of the bottom member 2 is a cylindrical element or bead 8, which lies in axial alignment with the two beads 7 when the container is closed, as shown in Fig. 2. When the container is in this closed position, the loop-shaped hasp can be swung to cause the same to fit around or extend under the bead 8, thus preventing the container sections 1 and 2 from being swung apart and accordingly hold the box in closed position. To open the box, the hasp 9 is swung outwardly, as shown in Figs. 1 and 4, so that it may be passed around the bead 8. To prevent the hasp from inadvertently opening, it is desirable that the pintles 10 operate with some friction within the tubular bead elements 7, thereby enabling the hasp to retain itself in either locked or open position when manually placed in either of said positions.

In the modified structure shown in Figs. 6 and 7, the top section 1 of the container is provided along its front edge with a tube 12 located in axial alignment with a similar tube 13 secured along the front edge of the lower section 2 of the container. Mounted for sliding movement within the tube 12 is a bolt 14 formed with an integral neck portion 15 slidable within a slot 17 formed in the wall of the tube 12. A finger-piece 16 constituting an integral extension of the neck 15, is disposed on the outer side of the tube 12 and constitutes a means by which the bolt may be manually shifted longitudinally of the tubes 12 and 13. The locked position of the device is shown in Fig. 6 wherein it will be seen that the bolt has been projected out of the tube 12 to an extent sufficient to cause it to enter tube 13, thus bridging the two tubes 12 and 13 and holding the two sections 1 and 2 of the container in locked relation. To open the locking device, the bolt is slid to the right, causing it to be withdrawn out of tube 13, and the two container sections can then be swung apart.

In the modification of the invention disclosed in Figs. 8 and 9, the top section or cover member 1 is provided at its front edge with a cylindrical element or bead 18, not necessarily tubular, and the bottom section 2 of the container is provided with a similar cylindrical element or bead 19. The inner end of the bead 19 is provided with an angular or bevelled end 21 frictionally co-operating with a similar angular or bevelled end 20 on the bead 18 so that when the two bevelled ends 20 and 21 are brought together, and the two beads 18 and 19 are axially aligned, the friction between bevelled ends 20 and 21 will be sufficient to retain the two halves or container sections together in closed position. This is facilitated by forming one of the bevelled ends at a slightly different angle to the other whereby friction between the two ends will be set up when the two container sections are brought together. With this type of locking means, no projecting parts or elements are present, and a smooth, continuous cylindrical beading is provided along both the front and rear edges of the container.

The structures shown in the several embodiments of the invention are such that all parts of the device including hinge and lock parts, may, if desired, be made of wood, plastic or similar materials, and the external appearance of the container is greatly enhanced by the absence of dissimilar materials and projecting parts.

What we claim is:

1. A vanity case or the like having a body composed of two hingedly connected sections, each section having a cylindrical beading disposed along one of its edges, the beading on one of the sections adapted to be disposed in axial alignment with that on the other section when the case is in closed position, the beading on one section adapted to be disposed between beading parts on the other section when the case is closed, and a pivoted locking link carried by one of the sections adapted to be swung over the beading on the other section when said beading is disposed between the bead-

ing parts on the section on which the locking link is carried.

5 2. A vanity case or the like made of wood or similar material having two sections hingedly connected together and having locking means disposed remote from the hinge, said locking means consisting of a cylindrical member on one of the case sections adapted to be disposed centrally between and in axial alignment with two spaced cylindrical members on the other section, and a hinged loop mounted in the two last mentioned cylindrical members and adapted to be swung to engage beneath the central cylindrical member to hold the sections of the case in locked relation.

10 3. In a container of the character described, a base portion and a top hingedly connected thereto, locking means for holding the top and base in closed position comprising, several aligned tubular sections provided along the front edge of one of the container sections, a cylindrical member provided along the front edge of the other section of the container, said cylindrical member being disposed between and in axial alignment with the tubular sections when the top and base of the container are in closed position, and a loop hasp member pivoted between the two tubular sections and adapted to be swung to embrace the cylindrical member when the top and base member of the container are in closed position and the cylindrical member is disposed in axial alignment with the tubular sections.

15 4. In a container of the character described, two container sections hingedly connected at one end, the front edge of each of the container sections being grooved, each of the grooves carrying cylindrical beading elements, the beading on one of the sections carrying a pivoted loop adapted to fit around the beading on the other section when the two container sections are in closed position and the beading on both sections is axially aligned.
